[57] CLAIM

The ornamental design for front leg shin guard for horses, as shown and described.

DESCRIPTION

FIG. 1 is a left side elevational view of a front leg shin-guard for horses showing our new design;

FIG. 2 is a front elevational view thereof;

FIG. 3 is a right side elevational view thereof;

FIG. 4 is a rear elevational view thereof;

FIG. 5 is a left side elevational view of a modified form of the shin-guard for horses shown in FIG. 1;

FIG. 6 is a front elevational view of FIG. 5;

FIG. 7 is a right side elevational view of 5; and

FIG. 8 is a rear elevational view of FIG. 5.

FIG. 1

FIG. 2

FIG. 3

FIG. 4

FIG. 5

FIG. 6

FIG. 7

FIG. 8
